United States Patent Office

Des. 186,334
Patented Oct. 13, 1959

186,334

ORGAN CONSOLE

William Millington, Grand Rapids, Mich., and Wilbur M. Day, Kenwood, Ohio, assignors to The Baldwin Piano Company, Cincinnati, Ohio, a corporation of Ohio

Application March 13, 1959, Serial No. 54,988

Term of patent 14 years

(Cl. D56—2)

FIG. 1.

FIG. 2.

FIG. 3.

Fig. 1 is a perspective view of an organ console, showing our new design.

Fig. 2 is a partial plan view showing the shape of the side element and arm of the organ console.

Fig. 3 is a partial end elevation of the organ console. We claim:

The ornamental design for an organ console, substantially as shown.
